UNITED STATES PATENT OFFICE.

DE WITT CLINTON PRESCOTT, OF MARINETTE, WISCONSIN.

OFFSET MECHANISM FOR SAW-MILL CARRIAGES.

SPECIFICATION forming part of Letters Patent No. 378,717, dated February 28, 1883.

Application filed November 9, 1887. Serial No. 254,707. (No model.)

To all whom it may concern:

Be it known that I, DE WITT CLINTON PRESCOTT, a citizen of the United States, residing at Marinette, in the county of Marinette and State of Wisconsin, have invented a certain new and useful Improvement in Offset Mechanism for Saw-Mill Carriages, which is fully set forth in the following specification, reference being had to the accompanying drawings, in which—

Figure 1 is a plan view of a saw-mill carriage embodying my invention; Fig. 2, a sectional view taken on the line 1 1 of Fig. 1, and on an enlarged scale; Fig. 3, a transverse sectional view taken on the line 2 2 of Fig. 1; Fig. 4, a central transverse sectional view of the cam-shifting device; Fig. 5, a plan view of the elements of the shifting mechanism detached; Fig. 6, a sectional view of the same, taken on the line 3 3 of Fig. 5; Fig. 7, a view of a modified form of shifting device; Fig. 8, a plan view of the mechanism on the carriage proper co-operating therewith; Fig. 9, a sectional view taken on the line 4 4 of Fig. 7, and looking in the direction of the arrow; and Fig. 10 a detail sectional view taken on the line 5 5 of Fig. 8.

Like letters refer to like parts in all the figures of the drawings.

My invention relates to saw-mill carriages, and more particularly to that class in which the carriage is provided with automatic means for shifting the log clear of the saw upon its return movement, and advancing the same to its original position upon its forward movement.

My present invention is in the nature of an improvement upon the apparatus set forth in an application for Letters Patent filed by me June 9, 1887, Serial No. 240,834, and has for its object to improve the construction therein set forth for imparting movement to the cam-shifting device in order to render the same more simple, cheap, and efficient in operation.

I will now proceed to describe a construction in which I have carried out my invention in a practical way, and will then particularly point out in the claims those features which I deem to be new and desire to secure by Letters Patent.

In the drawings, A represents the frame of

the saw-mill carriage, this frame being of any approved construction, and being provided with the usual means for securing the log in position thereon and for setting it up to the saw at each cut. This frame is mounted on a series of trucks composed of axles B, each provided with wheels b and b', secured thereon and revolving therewith. These wheels travel upon the rails C and C', the said wheels and rails being constructed in any approved form, although I prefer that shown, in which one of the rails, as C', is provided with a projecting rib, while the corresponding wheel, b', is grooved to fit upon the rib and prevent lateral displacement of the trucks.

The carriage A is free to move laterally upon the axles, so as to clear the log of the saw upon the return movement of the carriage, and allow it to be moved up into position again upon the forward movement. In order to effect this lateral movement of the carriage, I employ cam-shifting devices mounted on one or more of the axles and constructed substantially as in my application for Letters Patent hereinbefore referred to. In this construction D represents a sleeve mounted loosely on the axle, so as to be capable of a rocking or oscillating movement around the same, and provided on its upper side with a cam-groove, D', formed by means of parallel inclined projections D². A transverse beam, E, on the carriage-frame A is provided with a roller, E', which enters between the inclined projections D², and thus engages the cam-groove D' formed thereby. These parts just described are constructed substantially in the same manner as set forth in my application hereinbefore referred to, and therefore need no detail description here.

In order to operate the sleeve D, I employ collars F, mounted on the axle B at each end of the sleeve, fixed on the said axle so as to rotate therewith, and having a frictional contact with the ends of the sleeve sufficient to actuate the same within the limits of its motion. The collars F are adjustable upon the axle B, being secured thereon after adjustment by means of set-screws f. In order to obtain an efficient friction-surface, I form upon each collar a friction-disk, F', provided with a projecting marginal flange, f', and I form upon the adjacent end of the sleeve D a correspond-

ing friction-disk, D^3 , over which the flange f' projects slightly when the parts are in position, so as to protect the friction-surfaces. Between the friction-disks F' and D^3 , I prefer 5 to employ a washer, F^2 , constructed of wood, vulcanized fiber, or other suitable material, which serves to increase the friction between the disks, this washer lying in a suitable 10 groove, f^2 , in the friction-disks F' . In order to provide means for adjusting the frictional 15 contact between the collars and the sleeve, independently of the adjustment of the collars on the axle B, I make the groove f^2 in one of the friction-disks F' of increased depth, and 20 locate therein a metallic annulus, F^3 , against the back of which bear springs f^3 , arranged 25 in suitable housings, F^4 , provided with screw-caps f^4 , by means of which the pressure of the springs upon the annulus F^3 may be nicely 30 regulated. Each of the sleeves D is provided 35 with a downwardly-extending arm, D^4 , to the lower end of which is pivoted one end of a connecting-rod, G, the other end of which is 40 connected to a vibrating arm, H, mounted in 45 a suitable bearing, H' , on the frame A.

In the construction shown in Figs. 1 and 2, in which two cam-shifting devices are employed, one at each end of the carriage-frame, the two connecting-rods G are both connected 30 to the same vibrating arm H, which arm is located at about the middle of the carriage-frame.

H^2 represents adjustable stops, constructed substantially as in my application for Letters 35 Patent hereinbefore referred to, and serving by their contact with the projecting upper end of the vibrating arm H to limit the motion of the same, and consequently the motion of the sleeves D.

40 H^3 represents a lock consisting of an L-shaped arm pivoted on the housing of one of the stops H^2 , or any other suitable base, and serving, when hooked or caught over the upper end of the vibrating arm H, to lock the same, and thereby prevent any rotation of the sleeves D.

The location and construction of the lock and stop mechanism which I have just described is the one which I prefer, chiefly for 50 the reason that it locates these parts at the middle of the carriage, where they are within convenient reach of the operator, who is seated upon the carriage at this point and may reach the lock without leaving his seat. In case, 55 however, a more compact form is desirable, as, for instance, where the device is to be applied to a saw-mill carriage already in use—in which instance it is desirable to have the whole device self-contained and capable of 60 ready application as a whole—I may employ the modified form of apparatus shown in Figs. 7 to 10 of the drawings. In this construction the stops H^2 are mounted on the cross-beam E, on opposite sides thereof, and also preferably 65 on opposite sides of the axis of the roller E'. I also form upon the sleeve D projecting wings I, arranged on opposite sides thereof, as

shown, and in line with the respective stops H^2 , which limit their motion.

J indicates a locking-arm secured on a short 70 rock-shaft, J', which is mounted in bearings j on the beam E, and is provided with a handle or lever, j', for operating the same. This locking-arm may be swung down into the position shown in full lines in Fig. 9 of the drawings, to bear upon the arm I, and thus lock the cam-shifting device during the return-motion of the carriage; or it may be swung out into the position shown in dotted lines, when the said shifting device is free to operate. 80

The operation of the apparatus is as follows: When the carriage starts upon its forward travel to make the first cut, the collars F will, by reason of their frictional engagement with the sleeves D, rotate the same along with the 85 axles B to the extent permitted by the stops H^2 , and this motion of the sleeves will, by reason of the cam-grooves thereon, impart to the frame A a lateral movement upon the axles B sufficient to present the log to the saw in 90 proper position to make the first cut. When the carriage has completed its forward journey and the direction of its travel is reversed, the collars F will, by reason of their engagement with the sleeves D, impart a partial 95 movement of rotation to said sleeves in the reverse direction, and will move the frame A bodily upon the axles away from the saw, thereby clearing the log from the saw and preventing any contact between them during 100 the return movement of the carriage. When the carriage has completed its forward journey and the direction of its travel is reversed, the collars F will, by reason of their engagement with the sleeves D, impart a partial 95 movement of rotation to said sleeves in the reverse direction, and will move the frame A bodily upon the axles away from the saw, thereby clearing the log from the saw and preventing any contact between them during 100 the return movement of the carriage. It will be observed that by arranging the friction-collars at the ends of the sleeves I not only obtain a much more simple and compact device, but I also utilize the lateral thrust which 105 the rollers E' exert upon the inclines D^2 to press the sleeves more firmly against the friction-collars, and thus obtain a better contact, whereby the efficiency of the device is increased. It will be understood, of course, that 110 when the sleeves have reached the limit of their motion in either direction the frictional contact between the collars and the said sleeves is not sufficient to prevent the free rotation of the axles and the further travel of the 115 carriage.

The locking device is chiefly employed in the case where, when a cut has been partially made, it is desired to withdraw the log without completing the cut. In this case it is of course necessary that no lateral motion of the carriage should occur, and that the saw should pass out of the kerf already formed, and this is effected by locking the shifting device by the means already described, so that when the motion of the carriage is reversed no lateral movement of the carriage-frame will occur. 125

It is obvious that various modifications in the details of construction may be made without departing from the principle of my invention, and I therefore do not wish to be understood as limiting myself strictly to the precise details hereinbefore described, and shown in the drawings. 130

Having thus described my invention, what I claim as new, and desire to secure by Letters Patent, is—

1. In a saw-mill carriage, the combination, 5 with the truck-axles, of the carriage-frame capable of lateral movement on the axles, one or more cam-shifting devices mounted loosely on the axles, corresponding projections connected to the carriage-frame and engaging said cam-shifting devices, and friction-collars secured on the axles at each end of the cam-shifting devices to operate the same, substantially as and for the purposes specified.
2. In a saw-mill carriage, the combination, 15 with the truck-axles, of the carriage-frame capable of lateral movement on the axles, one or more cam-shifting devices mounted loosely on the axles, corresponding projections on the carriage engaging said cam-shifting devices, stops to limit the motion of the cam-shifting devices, and friction-collars secured on the axles at each end of the cam-shifting devices to operate the same, substantially as and for the purposes specified.
- 25 3. In a saw-mill carriage, the combination, with the truck-axles and the carriage-frame capable of lateral motion thereon and provided with a projection, of a sleeve mounted loosely on one or more of the axles and provided

with a cam-groove with which the said projection engages, friction-disks on the ends of the said sleeve, and collars secured on the axle at each end of the sleeve and provided with friction-disks to bear against the corresponding disks on the sleeve, substantially as and for the purposes specified.

4. The combination, with the truck-axle B and the carriage-frame laterally movable thereon and provided with a suitable projection, of the sleeve D, mounted loosely on the axle and provided with a cam-groove to receive the projection, the end friction-disks, D³, the collars F, secured on said axle at each end of the sleeve and having flanged disks F', and the washers F², arranged between the said disks, substantially as and for the purposes specified.

5. The combination, with the axle B, sleeve D, with friction-disks D³, and collars F, with friction-disks F', of the washers F², the annulus F³, arranged behind one of said washers, and the springs f³, of adjustable tension, for regulating the friction, substantially as and for the purposes specified.
